Inventor

CHARLES BLIEBERGER

By his Attorney
Adolph L. Thomas.

UNITED STATES PATENT OFFICE.

CHARLES BLIEBERGER, OF NEW YORK, N. Y., ASSIGNOR OF FORTY-FIVE PER CENT TO
ADOLPH A. THOMAS, OF NEW YORK, N. Y.

SOUND AMPLIFIER.

Application filed February 19, 1923, Serial No. 619,826. Renewed April 27, 1926.

My invention is for a new and improved amplifier for use in phonographs, radio loudspeakers, and the like. The amplifier of my present invention is greatly superior to 5 ordinary horns in quality of reproduction, and yet possesses sufficient volume, at the same time being compact in construction.

The objections to horns or megaphones as sound amplifiers are too well known to require explanation here. We are all familiar with the undesirable "horny" and harsh quality of sound issuing out of a horn. Manufacturers of phonographs and radio loudspeakers have long been aware of these 15 inherent drawbacks in horns and have resorted to various expedients in an endeavor to improve their tone quality.

In my prior Patents No. 1,425,505, dated August 15, 1922, and No. 1,436,080, dated 20 November 21, 1922, I have set forth and claimed broadly sound-amplifying apparatus comprising a sound-receiving chamber and a plurality of sound compartments in communication with said chamber and open 25 to the outer air. This causes a diffusion or distribution of sound and results in a reproduction of improved tone quality, as I have repeatedly demonstrated.

In the present invention I make use of the 30 foregoing principle to provide a construction particularly adapted to be easily substituted in phonograph and radio cabinets in place of the horns previously employed, and with practically no alterations in the 35 cabinet itself. This ready installation of my amplifier in cabinets of approved size and design is an important advantage from a commercial standpoint.

Briefly stated, my present invention comprises a diverging sound-conveying member 40 having lateral openings, through which sound waves pass into the space or compartment formed between the walls of said member and the walls of the box or cabinet in 45 which the member is mounted. Over the lateral sound openings, and spaced therefrom, are vibratory panels. At the outer end of the sound-conveying member are openings through which the space or compartments around the member communicate 50

with the free air. In this way, the sound waves issuing out of the conveying member and those issuing out of the surrounding space or compartments pass into the free air through the usual opening in the 55 front wall of the cabinet. This eliminates the necessity of providing sound outlets in the sides or corners of the cabinet, and permits installation of the invention in cabinets of prior or standardized design.

My present invention is also applicable to horns which are not enclosed in boxes or cabinets,—for instance, horns in radio loudspeakers. The tone quality of such horns is greatly improved by providing them with 60 lateral sound openings and mounting vibratory panels over the openings, the panels being spaced from the walls of the horn. These panels may be mounted inside or outside of the horn; or, some of the panels may be 65 inside and others outside of the horn.

In order to explain my invention, so that those skilled in the art may construct and use the same, I shall describe in detail the embodiment shown in the accompanying 70 drawings, in which

Fig. 1 is a top plan view in cross-section, approximately on line 1—1 of Fig. 2, showing a form of my new sound amplifier enclosed in a phonograph cabinet;

Fig. 2 is a vertical cross-section approximately on line 2—2 of Fig. 1, looking in the direction of the arrows and showing a side view of the amplifier;

Fig. 3 is a cross-section approximately on 80 the broken line 3—3 of Fig. 1, the cabinet being omitted for the sake of clearness; and

Fig. 4 is a front view of the amplifier shown in the preceding figures.

In Figs. 1 and 2, there is a cabinet indicated as a whole by C, which in this instance is a phonograph cabinet of suitable design and proportions. Any kind of box or cabinet may be used to enclose the amplifier. Within the chamber 1 of cabinet C is 90 mounted a sound-conveying member indicated as a whole by S. This member, which has the general shape of a horn, consists of walls 2, 3, 4 and 5. These walls extend rearwardly and upwardly to form a throat or 95 100

passage 6, which is open at 7 to permit communication with the tone arm 8 or with any suitable source of sound to be amplified.

In the drawings, the horn S is of rather 6 peculiar design, and is arranged obliquely within the cabinet. This particular shape and arrangement is merely incidental, and is for the sole purpose of accommodating the tone arm 8 in proper position with the respect to the turntable 9 of the phonograph.

The sound chamber or horn S may be made symmetrical or in any other desired shape, depending upon the size, style and proportion of the particular cabinet in which the 10 horn is to be enclosed.

The walls of the horn S are provided with sound openings 10. In the drawings I have shown two openings in each wall, and these openings run generally in an axial direction, 20 diverging toward the mouth of the horn. It should be understood, however, that the number, shape and arrangement of the openings may vary in accordance with the size and shape of the horn. Also, the particular 25 acoustic effect desired to be produced may be a factor in regard to the openings 10. I may also provide openings in the corners of the walls, and some of the openings may converge toward the mouth of the horn, while 30 others may converge in the opposite direction. I mention this merely as illustrative of the changes that may be resorted to.

Over the openings 10 in the walls S are mounted panels 11, 12, 13 and 14. These 35 panels are preferably, but not necessarily, secured to the walls of the horn by any suitable means, such as screws or bolts 15. Sleeves or bushings 16 hold the panels properly spaced from their respective walls, 40 so as to form sound chambers or spaces 17 between the horn and the panels. Personally I prefer to mount the panels obliquely with respect to the walls of the horn, so as to make the sound chambers pyramidal or 45 diverging. The shape of the panels 11, 12, 13 and 14 will, of course, depend on the shape of the horn and also upon the size, shape and arrangement of the sound openings 10. As shown in Fig. 2, the panel 13 50 is cut away at 18 to accommodate the motor M of the phonograph.

The panels 11, 12, 13 and 14 are preferably of wood and sufficiently thin to be vibratory under the action of sound waves. The spacing members 16 may be of suitable sound-absorbing material, such as rubber, leather, felt and the like, although that is not absolutely necessary. Although I have shown the panels mounted outside the horn, I may 55 mount them on the inside. In fact, some of the panels may be supported outside the horn and others inside. So when I say that the panels are mounted over the openings 10, I mean broadly that they are arranged

across the openings, whether inside or outside the horn.

The box or cabinet C has a front opening 19 at which the mouth of the horn S terminates. In practice the mouth of the horn is practically coextensive with the opening 70 19. When I refer to the opening 19 as a front opening, I use the expression merely in a relative sense. The outer edges of the walls 2, 3, 4 and 5 of amplifying member S are cut away, as indicated at 20. The purpose of the cutaway portions 20 is to provide sound outlets between the space or chambers around the horn S and the free outer air. In Fig. 4, these sound outlets are 75 indicated at 21. In the construction illustrated in the drawings, the sound outlets 21 are formed by cutting away the outer edge of the horn S in an oblique direction. However, that is not necessary, and I would have it understood that communication between the free air and the sound chambers surrounding the amplifier S may be established 80 in any other suitable way.

In the operation of my new amplifying device, as the sound waves enter the horn S at the smaller end thereof, they pass in part through the openings 10. The impact of the sound waves against the panels 11, 12, 13 and 14 will cause the same to vibrate if they are of a vibratory material. In any event, the air in the spaces or chamber 17 between the horn and the panels is set in vibration and the waves spread in part into the spaces or chambers formed between the horn and the walls of the enclosing box or cabinet. From the sound chambers surrounding the horn, the sound waves pass into the outer air through the outlets 21. The opening 19 of the cabinet is thus a common outlet for the sound waves entering the neck of the horn. Some or a part of the waves entering the horn will pass directly through the horn into the outer air, while a portion of the waves will pass through the openings 10 and reach the outer air through the outlets 21. The proportion of sound waves passing through the openings 10 will depend mainly upon the size, shape and arrangement of the openings.

Although I have referred to the sound-conveying member S as a horn, I use the term merely for convenience. As a matter of fact, the member S has none of the objectionable acoustic properties of horns as heretofore constructed. It is a matter of common knowledge among those skilled in the art that ordinary horns, such as are found in prior phonographs and radio loud-speakers, give a decidedly unnatural reproduction, which is commonly referred to as "horny". For instance, the characteristic "horny" sound of a phonograph is recognizable even at a distance. According to my present invention, I can utilize a horn as 115 120 125

heretofore constructed—say, for instance, the horn of a standard make of phonograph—and embody therein the features of my invention as above explained. No 5 changes in the outside of the cabinet are necessary, my construction being substituted for the old horn in the same space previously occupied by that horn. This ready substitution of my invention for the old types of 10 horn is an important factor from a commercial standpoint, for it enables manufacturers of sound-reproducing apparatus to maintain their standardized form of cabinet.

To cite an instance of the practical application of my invention, I took the horn out 15 of a standard and widely known make of phonograph, utilized the horn in constructing my invention, and replaced the new construction in the cabinet without any visible 20 changes in the appearance of the cabinet. Actual tests demonstrated that the reproduction given by my new amplifier had a tone quality far superior to that of the old horn.

25 In general, I may say that my new sound amplifier does away with the harsh and "choky" reproduction of horns, and produces tones distinguished by a clear and natural quality. The volume of the reproduced 30 sounds depends upon the characteristics of the vibrations that enter the amplifier and upon the general shape and size of the device, and perhaps also upon other minor factors.

35 In the broader aspect of my invention, the amplifying member S need not be encased in a box or cabinet. For instance, in the smaller types of radio loudspeakers, my new 40 amplifier may be supported in an upright position on a suitable base, without being enclosed in a box.

Although I have herein shown and described a certain specific construction, I 45 would have it understood that I have done so merely to explain my invention so as to enable those skilled in the art to practise the same, and not by way of limitation or restriction. It is obvious that the underlying 50 idea of my invention may be mechanically carried out in other ways than herein set forth.

I claim as my invention:

55 1. A sound-amplifier comprising walls arranged to form a substantially pyramidal sound chamber adapted to be connected with a source of sound, said walls being provided with sound openings, and vibratory panels arranged over said openings and spaced from said walls, said panels extending along 60 said walls in the general direction thereof and permitting escape of sound waves laterally into the free air.

65 2. A sound-amplifier comprising walls arranged to form a diverging sound chamber,

said walls being provided with sound openings, and vibratory panels secured to said walls opposite said openings and spaced from said walls, said panels extending along said walls in the general direction thereof and permitting escape of sound waves laterally into the free air. 70

3. A sound-amplifier comprising a horn provided with elongated lateral sound openings extending generally lengthwise of the horn and panels arranged over said openings, said panels being spaced from the horn to provide sound chambers open to the free air. 75

4. A sound-amplifier comprising a horn provided with lateral sound openings and with panels arranged over said openings, said panels being secured to and spaced from the horn to provide sound chambers open to the free air. 80

5. A sound-amplifier comprising a box or cabinet having an opening in its outer wall, an outwardly diverging sound-conveying member mounted in said cabinet so that the mouth of said member terminates substantially at the outer opening of the cabinet, 85 there being a space between the walls of said cabinet and the walls of said member to form sound chambers, said member being provided with lateral openings through 90 which sound waves pass into said chambers, and means whereby said chambers communicate with the free air through said outer opening in the cabinet. 95

6. A sound-amplifier comprising a box or cabinet having an opening in its outer wall, an outwardly diverging sound-conveying member mounted in said cabinet so that the mouth of said member terminates substantially at the outer opening of the cabinet, 100 there being a space between the walls of said cabinet and the walls of said member to form sound chambers, said member being provided with lateral openings through 105 which sound waves pass into said chambers, and sound outlets at the outer end of said member for placing said chambers in communication with the free air. 110

7. A sound-amplifier comprising a box or cabinet having an opening in its outer walls, an outwardly diverging sound-conveying member mounted in said cabinet so that the mouth of said member terminates substantially at the outer opening of the cabinet, 115 there being a space between the walls of said cabinet and the walls of said member to form sound chambers, said member being provided with lateral openings through 120 which sound waves pass into said chambers, the outer edge of said member being cut away to provide sound outlets between said 125 chambers and the free air.

8. A sound-amplifier comprising a box or cabinet having an opening in its outer wall,

- an outwardly diverging sound-conveying member mounted in said cabinet so that the mouth of said member terminates substantially at the outer opening of the cabinet, there being a space between the walls of said cabinet and the walls of said member to form sound chambers, said member being provided with lateral openings through which sound waves pass into said chambers, vibratory panels arranged over said lateral openings and spaced therefrom, and sound outlets at the outer end of said member for placing said chambers in communication with the free air.
9. A sound-amplifier comprising a box or cabinet having an opening in its outer walls, a sound-conveying member mounted in said cabinet so that the mouth of said member terminates substantially at the outer opening of the cabinet, there being a space between the walls of said cabinet and the walls of said member to form sound chambers, said member being provided with lateral openings through which sound waves pass into said chambers, the outer edge of said member being cut away to provide sound outlets between said chambers and the free air, and panels mounted over said lateral openings and spaced from the walls of said member.
10. A sound-amplifier comprising a box or cabinet having an opening in its outer wall, an outwardly diverging sound-conveying member mounted in said cabinet so that the mouth of said member terminates substantially at the outer opening of the cabinet, there being a space between the walls of said cabinet and the walls of said member to form sound chambers, said member being provided with lateral openings through which sound waves pass into said chambers, panels arranged in said chambers opposite said lateral openings and spaced from said openings, and sound outlets at the outer end of said member for placing said chambers in communication with the free air.
11. A sound-amplifier comprising a box or cabinet having an opening in its outer wall, a sound-conveying member mounted in said cabinet so that the mouth of said member terminates substantially at the outer opening of the cabinet, there being a space between the walls of said cabinet and the walls of said member to form sound chambers, said member being provided with lateral openings through which sound waves pass into said chambers, vibratory panels arranged over said lateral openings and spaced therefrom, and means whereby said chambers communicate with the free air through said outer opening in the cabinet.
12. A sound-amplifier comprising a box or cabinet having an opening in its outer wall, an outwardly diverging sound-conveying member mounted in said cabinet so that the mouth of said member terminates at the outer opening of the cabinet, there being a space between the walls of said cabinet and the walls of said member to form sound chambers, said member being provided with lateral openings through which sound waves pass into said chambers, means whereby said chambers communicate with the free air through said outer opening in the cabinet, and panels secured to and spaced from the walls of said member opposite said lateral openings.
13. A sound-amplifier comprising walls arranged to form a sound-receiving chamber adapted to be connected with a source of sound, other walls arranged to form sound compartments around said chamber, there being openings through which said chamber communicates laterally with said compartments, and panels mounted over said openings and spaced therefrom, said chamber and said compartments being open to the free air.
14. A sound-amplifier comprising walls arranged to form a sound-receiving chamber adapted to be connected with a source of sound, other walls arranged to form sound compartments around said chamber, there being openings through which said chamber communicates laterally with said compartments, and panels mounted on said first mentioned walls over said openings and spaced from said walls, said chamber and said compartments being open to the free air.
15. A sound-amplifier comprising walls arranged to form a sound chamber adapted to be connected with a source of sound, said walls being provided with sound openings, and panels arranged over said openings and spaced from said walls, said panels approximately paralleling and extending along said walls in the general direction thereof and permitting escape of sound waves laterally into the free air.
16. A sound-amplifier comprising a horn provided with elongated sound openings extending generally lengthwise of the horn and panels arranged over said openings, said panels being spaced from the horn to provide a sound chamber open to the free air.
17. A sound-amplifier comprising walls arranged to form a sound chamber adapted to be connected with a source of sound, certain of said walls being provided with a sound opening, and panels positioned over said openings and spaced from said walls permitting the escape of sound waves into the free air, said panels paralleling said walls and extending in the general direction thereof.
18. A sound-amplifier comprising walls arranged to form a sound chamber and adapted to be connected with a source of sound, certain of said walls being provided

with a sound opening, and means positioned over said openings and spaced from said walls permitting the escape of sound waves into the free air, said means approximately 5 paralleling said walls and extending in the general direction thereof.

19. A sound-amplifier comprising walls arranged to form a sound chamber and

adapted to be connected with a source of sound, certain of said walls each being provided with at least one elongated sound opening extending generally lengthwise of the horn and means cooperating with said openings permitting the escape of sound waves into the free air. 10

CHARLES BLIEBERGER.
